UNITED STATES PATENT OFFICE

ANTHONY F. G. LUCAS, OF WASHINGTON, DISTRICT OF COLUMBIA

DESIGN FOR A CHAIR

Application filed December 8, 1930. Serial No. 37,918. Term of patent 14 years.

To all whom it may concern:

Be it known that I, ANTHONY F. G. LUCAS, a citizen of the United States, residing at Washington, in the District of Columbia, have invented a new, original, and ornamental Design for Chair, of which the following is a specification, reference being had to the accompanying drawings, forming part thereof.

Fig. 1 is a side view, and Fig. 2 is a front view of a chair showing my new design.

I claim:

The ornamental design for a chair as shown.

ANTHONY F. G. LUCAS.
